AIRCRAFT GUN PORT OPENING AND CLOSING DEVICE CONTROLLED BY GUN TEMPERATURE

Robert R. Beachler, Jr., Santa Monica, and John M. Oberholtzer, Los Angeles, Calif., assignors to the United States of America as represented by the Secretary of the Air Force

Application April 13, 1950, Serial No. 155,721

4 Claims. (Cl. 89—37.5)

1

In high speed aircraft, it has been found desirable to provide closures for the gun blast tube opening. If such openings were not closed while the guns were not in operation, a serious decrease in aerodynamic efficiency would be caused by the open ports. On the other hand, if such ports are closed while a cartridge is being fired from a gun, serious disruption of the airplane structure may occur, which may conceivably lead to the loss of the airplane and its personnel.

One object of the present invention is to provide a device which will open the gun ports when the gun mechanism is actuated.

Another object of the invention is to provide a mechanism that will close the gun ports after the gun has ceased to fire, but will keep them open so long as there is any danger of a heat-induced explosive discharge resulting from leaving a cartridge in a hot barrel chamber. Such discharge is commonly known as a "cook-off."

Another object of the invention is to provide a device of the above character in which the rate of cooling of the device may be synchronized with the rate of cooling of the gun barrel, particularly the chamber thereof, both when the ship is in the air and when it is on the ground. The two rates of cooling are greatly different in such case.

Another object is to provide a device of the above character which does not employ thermocouples. Thermocouples have been found to be unreliable in this kind of duty, due to severe vibration to which the guns and other parts of the airplane are subjected.

The present arrangement, briefly described, provides such a control wherein an electrical unit comprising a thermal computing relay (Thomas A. Edison, Inc. Model 501) is utilized to simulate the heating and cooling rates of the guns. The relay has a pair of contacts, which are normally closed, one of which is mounted on a bi-metal strip which is wound with a heating coil. This heater is energized concurrently with the firing of the guns. As firing continues, the bi-metallic element is heated until contact is broken. Such action de-energizes the door-closing circuit but does not interrupt firing or cease heating the bi-metallic element. The heat transfer of the unit occurs at a rate comparable to the cooling of the guns and upon cessation of firing the bi-metallic element cools. Resumption of firing may, however, further heat the bi-metal strip and prolong the cooling period required before the doors will close. In addition to the above mentioned bi-metal strip and heater, the fixed contact is carried on a second bi-metallic member which com-

2

pensates for over-all temperature variations within the unit (not shown). The entire assembly is inclosed in a vacuum-tube-envelope, whereby the desired slow cooling-rate is obtained.

5 The thermal computing relays of the kind described are included in the system disclosed. One of these is comparable to the ground cooling-rate for the guns, while the other is arranged to simulate the cooling-rate while the aircraft is in the air. The relay contacts are adjusted to open before the gun temperature rises into the critical zone where there is danger of a "cook-off," therefore preventing the door-closing mechanism from being actuated. These contacts are held open until the danger has passed and the temperature has been reduced below a safe limit whereupon the normal actuation of the doors is resumed. An additional time delay relay for power control is provided. It tends to minimize the effects of vibration and marginal contact conditions.

10 Referring now to the accompanying drawings, Fig. 1 is a schematic diagram showing the electric circuit through which the objects of the invention are achieved. The relays, switches, etc., are shown in their normal positions i. e. those assumed when no current is flowing in the circuit.

15 Fig. 2 is a fragmentary view of an airplane in side elevation, to which the invention has been applied. An access door is shown open, through which opening the guns may be seen.

20 Fig. 3 is a gun-port door closing actuator or mechanism and 11 is a gun-port door opening actuator or mechanism. These are not further described because they are conventional in various forms. One form is illustrated in Patent 2,428,359 as element 86, Figs. 7 and 8 of that patent. In the present figure, 10 and 11 are both grounded but are served by conductors 12 and 13 from sources A and B, respectively. Current flow in conductor 25 12 is under the immediate control of a relay 14 coil which in turn is under control of a second or thermal element-sensing relay 15 through a lead 16.

25 The door opening actuator 11 and door closing actuator 10 are under the control of relay 17. The coil 18 of the relay 17 is grounded at 19. Relay coil 18 controls the 0.10 second slow-break-relay-contacts 21 and simultaneously relay contacts 22 which control respectively the port opening actuator 11 and the door closing actuator 10 from sources of D. C. B and A respectively which may be of 28 volts.

30 The source B of direct current supplies a pair of identical thermal computing relays 25 and 26 which are effective respectively in the air and on

the ground to control delivery of current to the gun port door closing mechanism 10 a predetermined variable period of time after cessation of gun firing. The relays 25 and 26 are respectively provided with movable sets of contacts 29 and 30 which are mounted on thermostatic metal strips one of which is subject to ambient temperature conditions and the other wound with an electric heater coil, such heaters being indicated at 27 and 28 respectively. The heaters 27 and 28 are adjusted to heat and cool at the same rate as the gun barrel when the latter is respectively air-borne with the airplane or substantially stationary on the ground. The contact pairs 29 and 30 are arranged to be normally closed, i. e., when cool and to open when the heaters 27 and 28 have attained a critical temperature.

Source B supplies contact pairs 29 and 30, respectively, of the parallel-connected relays 25 and 26 with current whereby to energize relay coil 31. The latter is supplied through leads 32, 33 and 50 when the armature 34 of an air-ground transfer relay 35 is on the "ground" contact 36 as shown. When the relay armature 34 is in the "air" position, i. e., in contact with terminal 37, at end of lead 38, no ground thermal relay connection is provided.

A switch 39 is arranged to be open when the ship is on the ground or when the landing gear (not shown) is lowered. A spring 40 is provided to return it to closed position when the airplane is in the air. Ground connection is provided by switch 39 for the relay coil 41, energizing the latter from a third D. C. source C. Heating current for the heating elements 27 and 28 of thermal relays 25 and 26, respectively, is provided through a lead 43 from source B. Source B is connected to a set of contacts 44 of the relay 15 through a lead 45. The opening mechanism control and power relay unit 17 is connected to the thermal element sensing relay 15 through the lead 46. A gun-firing relay 47 may be energized from source B. A gun firing switch 48 is provided to conduct current from source B through the second set of contacts 49 of the relay 15, lead 46, contacts 21 and lead 13, thereby completing the circuit to the gun port door opening mechanism 11.

Referring now to Figure 2, in which actual adaptation of the just described structure to an airplane is shown: In the figure, 100 is the airplane fuselage in which there is a cabin 101, containing a steering wheel 102, on which there is mounted a gun trigger or firing switch 48. The switch 48 controls the firing of the machine guns 103, which are mounted in a compartment 104 closable by a door 105. The airplane is provided with a landing gear 106, which is foldable as shown in dashed line at 107, into the wings one of which is 108. The guns 103 are arranged in a partially-shown forward framework or support 109 to fit into ports which are closable by gun port doors 110 each covering a gun port 110'. Each door 110 is governed by an actuator 111, which here represents both the opening mechanism 11 and the closing mechanism 10. The relays and other electrical components may be contained in a box 112 which may be mounted inside the gun compartment 104.

Operation

When it is desired to fire the gun or guns, switch 48 is closed. From this point on, four cases are possible, i. e.,

(A) The airplane is on the ground and not firing,

- (B) The airplane is in the air and not firing,
- (C) The airplane is in the air firing, and
- (D) The airplane is on the ground firing.

Since the last case seldom occurs, description of the circuit occurrences which make it possible will be omitted. The remaining cases are however below described:

(A) *The airplane is on the ground and not firing.*—The relay 35 is closed upwardly by the action of the landing gear on switch 39. Power from source B is applied through the contacts 30 and 33 of the lead 33 to energize the relay winding 31 of the relay 15, thereby closing the contacts 44 to the right. As a result, power from the source B is applied through the lead 16 to energize the winding 14a of the relay 14 to close the armature thereof and thus to apply power from source A through the armature 22 of relay 17 to close the gun port doors by means of the actuator 10.

(B) *The airplane is in the air and not firing.*—In this case the switch 39 is closed by the action of the spring 40 thereby energizing the winding 41 of the relay 35 from the power source C, which closes the relay armature 34 downwardly. Consequently, power from source B is applied through the contacts 29 of the air computing relay 25 through the lead 38 to the switch contact 37 from which it passes through the lead 50 and the relay winding 31 to continue the energization thereof and the retention of the switch contacts 44 to the right and hence continues to energize the winding 14a of the relay 14 to hold closed the gun port doors by means of the actuator 10.

(C) *The airplane is in the air, firing.*—The switch 39 is held closed by means of the spring 40, the firing switch 48 is closed, power from source B is applied through the switch and through the lead 43 to the heating elements 27 and 28, which are in parallel, to ground. While the heating elements 27 and 28 are initially energized, the closed contacts 29 and 30 open after a critical temperature is reached. Upon separating, contacts 29 de-energize the relay winding 31 of relay 15, thereby causing the contacts 44 to close to the left. Power from the source B is then able to flow through the switch 48, the lead 43, the right hand movable contact 49 of the relay 15 to the lead 46 to energize the winding 18 of the relay 17 to armature 22 to so interrupt the application of power from source A via lead 51 to the armature of the relay 14. The winding 14a of relay 14 is now de-energized upon the de-energization of relay winding 31. Power from source B is also applied for 0.10 second across the relay armature 21 to actuate mechanism 11 to open the gun ports. The gun ports are held open by mechanism 11, as long as the switch 48 is held closed and 25 seconds longer, due to the continued heating of heating elements 27 and 28. After 0.10 second, the relay winding 18 opens the contacts 21 and 22 of the armature of relay 17. The gun port doors remain open during firing due to mechanism 11. 25 seconds after cessation of firing gun port closing mechanism 10 will operate provided critical temperature has not been reached. If critical temperature has been reached

contact 29 is open, thereby delaying closing of gun port doors until a safe (non cook-off) temperature has been reached. After safe temperature has been reached due to cooling, contact 29 closes and doors will close after normal 25-second delay.

What we claim is:

1. A gun port door controlling mechanism including actuating means for opening and closing a gun port door, a source of electric power, a first circuit for energizing said actuating mechanism in door opening direction, a gun-trigger-actuated switch for controlling said first circuit, a second circuit for energizing said actuating mechanism in the door closing direction, a thermal time delay relay for controlling said second circuit upon release of said trigger actuated switch and heater means energized by said trigger-actuated-switch for varying the time delay of said thermal relay in energizing said second circuit proportional to the time duration of closure of said trigger-actuated switch.

2. A control device for controlling aircraft gun port door actuating mechanism comprising in combination with said actuating mechanism an electric circuit including a source of power for energizing the door actuating mechanism in the opening direction, a trigger switch for controlling the energizing of said circuit, a second circuit including a power source for energizing said door actuating mechanism in the closing direction, a thermal time delay relay in said second circuit controlling the energization of said second circuit, said thermal relay having a pair of relatively movable circuit-controlling contacts, thermally responsive means for moving the contacts, and heater means energized under the control of said trigger switch to cause said thermally responsive means to move said contacts in one direction during closure of the trigger switch, the cooling rate of said thermally responsive means being equivalent to the cooling rate of airplane type machine guns after firing so that said second circuit cannot be energized by said contacts until the thermally responsive means has cooled to a predetermined temperature.

3. In combination in a device for opening and closing the doors of a gun compartment having one or more guns in said compartment, a door opening actuator, an electric circuit energizing said actuator, a slow break relay in said circuit, a door closing actuator, an electric circuit energizing said actuator, a pair of thermal computing relays selectively included in said circuit, one relay having the same cooling rate as possessed by the gun it serves when in flight in an airplane,

the other the same cooling rate as the gun after it is fired when in the same airplane on the ground, a switch common to both circuits, said switch being closed by the landing gear of the airplane when the airplane is on the ground, a relay for including the ground thermal computing relay in the circuits when said switch is closed and the air thermal computing relay in the circuits when the switch is open, a trigger switch and a safety switch for the gun, said switches being included in both of the foregoing circuits to control the output of either circuit to the gun.

5 4. In a device for opening and closing the doors of a gun compartment in an airplane in accordance with the temperature of a gun contained therein, said airplane having a foldable landing gear, the combination which comprises a door opening actuator, an electric circuit including slow break relay means for operating said actuator by the opening of said relay, a door closing actuator, an energizing circuit therefor, relay means included in said circuit to energize the circuit upon closing, a pair of thermal computing relays selectively included in said circuit, one 10 computing relay containing means to control by its cooling rate which is proportional to the cooling rate of the gun when the latter is not airborne the energizing circuit for said door closing actuator while the airplane is on the ground, the other computing relay containing means to control by its cooling rate which is proportional to the cooling rate of the gun when the latter is airborne the energizing circuit for said door closing actuator while the airplane is in the air, and 15 switch means controlled by the landing gear of the airplane for including the first thermal relay in said circuit when the landing gear of said airplane is down and for including the second thermal relay in said circuit when said landing gear is up.

ROBERT R. BEACHLER, JR.
JOHN M. OBERHOLTZER.
